US00D552097S

(12) **United States Design Patent** (10) Patent No.: **US D552,097 S**
(45) Date of Patent: **** Oct. 2, 2007**

(54) **SCANNER**

(75) Inventors: **Shoichi Ishizawa**, Asahi-mura (JP);
Hirokazu Yamano, Chino (JP)

(73) Assignee: **Seiko Epson Corporation** (JP)

(**) Term: **14 Years**

(21) Appl. No.: **29/242,594**

(22) Filed: **Nov. 10, 2005**

(30) **Foreign Application Priority Data**

Sep. 12, 2005 (JP) 2005-026338

(51) **LOC (8) Cl.** **14-02**

(52) **U.S. Cl.** **D14/425**

(58) **Field of Classification Search** D14/420,
D14/422, 424-25, 464, 453; D18/36-39;
235/470; 355/72, 75, 40; 358/474, 486,
358/488, 494, 497

See application file for complete search history.
